FIRING MECHANISM

George B. Davis, Jr., Washington, D. C., and
Isaac F. Rosenkrantz, Greenbelt, Md.

Application January 13, 1947, Serial No. 721,831

8 Claims. (Cl. 89—27)

(Granted under the act of March 3, 1883, as
amended April 30, 1928; 370 O. G. 757)

1

The invention described in the foregoing specification and claims may be manufactured and used by or for the Government for governmental purposes without the payment to us of any royalty thereon.

This invention relates to improvements in firing mechanism for guns, and particularly mortars.

An object of the invention is to provide selective means whereby a firing pin may be extended for drop firing and retracted for hand firing.

Another object of the invention is to provide a firing mechanism wherein the firing pin may be projected into the rear end of the gun barrel and held in position to detonate a primer in the base of a round, when the round gravitates into firing position.

Another object of the invention is to provide a firing mechanism wherein the firing pin may be retracted and held against the influence of a compressed firing spring and released at a desired time.

A further object of the invention is to provide positive cam-operated means for selectively reTRACTING or projecting the firing pin at the will of an operator.

A further object of the invention is to provide an emergency stop extension on the firing pin holder to prevent breakage of the moving parts, if excessive blow-back pressure is developed in the gun barrel.

A still further object of the invention is to provide a retractor spring on the firing pin whose bias is so proportioned to the bias of the firing spring, that the firing pin is caused to normally assume a partly retracted or neutral position.

A still further object of the invention is to provide closure means carried by the firing pin for preventing propellant gases from reaching the firing mechanism.

Other objects and advantages of the invention will be apparent during the course of the following description.

In the accompanying drawings, forming a part of this specification, and in which like numerals are employed to designate like parts throughout the same,

Figure 1 is an elevational view of a mortar barrel equipped with the present invention,

Figure 2 is a longitudinal sectional view taken on the line 2—2 of Figure 1,

Figure 3 is a transverse sectional view of Figure 2 taken on the line 3—3,

Figure 4 is a similar view taken on the line 4—4 of Figure 2,

2

Figure 5 is a similar view taken on the line 5—5 of Figure 2,

Figure 6 is a longitudinal sectional view taken on the line 6—6 of Figure 2 and showing parts in elevation,

Figure 6a is a development illustrating the relationship of the cocking pin, its slot and the cooperating cams in neutral position,

Figure 7 is a view similar to Figure 6 showing the firing pin in cocked position,

Figure 7a is a development illustrating the relationship of the cocking pin, its slot and the cooperating cams in cocked position,

Figure 8 is a view similar to Figure 6 showing the parts in fired position,

Figure 8a is a development illustrating the relationship of the cocking pin, its slot and the cooperating cams in fired position,

Figure 9 is a view similar to Figure 6 showing the firing pin locked in its forward position, and,

Figure 9a is a development illustrating the relationship of the cocking pin, its slot and the cooperating cams in the forward position of the firing pin.

In the drawings, wherein for the purpose of illustration, is shown a preferred embodiment of the invention, the reference character B indicates a barrel for guiding a projectile.

A breech closure 10 of cup-like formation is screw-threadedly connected to the barrel B at its forward end, and has a rearwardly extending portion 11. The portion 11 is bored and screw-threaded at 12 to receive the forward screw-threaded end of a tubular housing 13.

Formed in the breech closure 10 is a partition 14 having a forwardly extending boss 15 centrally of its forward face, for limiting the rearward movement of an inserted round (not shown).

Concentric with the longitudinal axis of the breech closure 10 and extending through the boss 15 is a bore 16, formed to slidably receive the reduced forward end 17 of a firing pin 18.

The tubular housing 13 is provided with a central longitudinal bore 19 concentric with the bore 16 in the boss 15. Slidable and oscillatable in the bore 19 is a cylindrical firing pin holder 20 secured to the rear end of the firing pin 18 by a pin 21. The rear end of the bore 19 is closed by a wall 22 between which and the rear end of the firing pin holder 20 a firing spring 23 is compressed.

Emergency stop means in the form of a rod 24, secured to the rear end of the firing pin holder 20, abuts the end wall 22 if excessive

blow-back pressure is developed in the gun barrel B.

The forward end of the bore 19 is counterbored as at 25 to form a seat for a sleeve 26 which acts as a stop shoulder for a collar 27 surrounding firing pin 18. A retractor spring 28 surrounds the firing pin 18 and is confined between the forward end of the firing pin holder 29 and the collar 27.

A cylindrical enlargement 29 formed on the firing pin 18 slides within the sleeve 26, and when the gun is fired, abuts the rear surface of the partition 14 adjacent the bore 16. The enlargement 29 also serves as a closure for the bore 16 to prevent propellant gases from entering the bore 19 and destroying the springs 23 and 28.

A stud 30 is secured to the firing pin holder 29 and extends radially therefrom through a longitudinal slot 31 in the tubular housing 13. The longitudinal slot 31 has oppositely extending circumferential branches 32 and 33.

Rotatably mounted exteriorly of the tubular housing 13 is a sleeve 34 having an internal annular groove 35 for receiving the outer end of the radially extending stud 30. The sleeve 34 is restrained against longitudinal movement by the rear portion 11 of the breech closure and by a stop enlargement 36 formed on the tubular housing 13. The annular groove 35 is formed with a longitudinal passageway 37 to facilitate assembly, and circumferentially extending enlargements including cam surfaces 38 and 39. One wall 40 of the passage-way 37 is extended forwardly and serves as a firing means when the stud 30 is seated in the branch 32 of slot 31, and the sleeve 34 is rotated in a counter-clockwise direction.

After a round is fired the sleeve 34 may be rotated in a clock-wise direction at which time the cam surface 38 will contact the stud 30 and return it to its cocked position in the branch 32 of the slot 31.

When the firing pin is in neutral position and it is desired to change to drop fire the sleeve 34 is rotated in counter-clockwise direction, forcing the cam surface 39 against the stud 30 and seating it in the branch 33 of the longitudinal slot 31. This operation will hold the forward end 17 of the firing pin in an extended position within the base cap.

Suitable indicia 41 is impressed on the outer circumference of the sleeve 34 adjacent the stop 36. A pointer 42 on the stop 36 registers with the indicia 41 when the sleeve 34 is rotated to clearly indicate the position of the firing mechanism.

A spring pressed detent 43 locks the tubular housing 13 to the rear portion 11 of the breech closure 10. The reduced tang of the detent projects radially outward of the breech closure and is fitted with a ring 44 for easy withdrawal of the detent from its locked position.

The operation of the firing mechanism is as follows:

Figures 2, 6 and 6a show the mechanism in a neutral or safety position. The bias of the retractor spring 28 resists the bias of the firing spring 23 sufficiently to keep the firing pin holder and its stud 30 in the position shown. The forward end 17 of the firing pin 18 is safely retracted within the bore 16 in the partition 14.

When it is desired to use the gun it is only necessary to observe the present position of the indicia 41 and pointer 42, to determine in which direction to rotate the sleeve 34.

If the mechanism is found to be in neutral

position, as shown in Figures 6 and 6a, and it is desired to operate the gun as a hand fired weapon, the sleeve 34 is rotated clockwise as viewed from the rear of the gun. This movement of the sleeve 5 causes the cam surface 38 to bear on the stud 30 and retract it in the slot 31 until the stud is seated in the branch 32 of the said slot, as shown in Figures 7 and 7a.

The firing mechanism is cocked by the above described movement of the sleeve 34 and cam 38, and when a round of ammunition (not shown) is placed in the barrel, the weapon is ready to be fired.

Counter-clockwise movement of the sleeve 34 10 15 will cause the wall 40 of the passageway 37 to bear against the stud 30, forcing it out of the branch slot 32 and into the slot 31. The firing pin holder 20, is then free to move forward under the bias of the firing spring 23 and force the firing pin through the bore 16 of the partition 14 into operative position, as shown in Figures 8 and 8a.

Figure 8 shows the position of the mechanism at the instant of firing. It will be seen in this 25 figure that the passage of propellant gases from the barrel is prevented by the enlargement 29 on the firing pin abutting the rear face of the partition 14 and sealing the bore 16.

After the force of the firing stroke has subsided in the firing pin and holder 20, the retractor spring 28 recovers and returns the mechanism to neutral position as shown in Figure 6. If desired the weapon may be cocked again by the method above described.

35 If it is desired to set the weapon for drop fire, as shown in Figures 9 and 9a, counter-clockwise movement is imparted to the sleeve 34. As has been described, the firing mechanism is normally in neutral position so that either method of 40 fire may be quickly selected by the simple operation of rotating the sleeve 34.

When the sleeve is rotated counter-clockwise the cam surface of the groove 35 bears against the stud 30, forcing it forwardly to project the 45 firing pin end 17 into the barrel. The stud 30 is also forced into the branch 33 of the slot 31 where it remains to lock the firing pin in operative position for drop fire.

It is to be understood that the form of the invention, herewith shown and described, is to be 50 taken as a preferred example of the same, and that various changes in the shape, size and arrangement of parts may be resorted to, without departing from the spirit of the invention, or the 55 scope of the subjoined claims.

We claim:

1. A gun firing mechanism comprising, a breech closure having an aperture therein, a generally tubular housing threadedly engaged with said closure including a longitudinal slot in the outer periphery thereof having oppositely extending circumferential branches adjacent to its opposite ends, a firing pin and holder secured together for joint reciprocation within said housing, a firing spring mounted for compression between said holder and an end wall of said housing, emergency stop means on said holder, shoulder means in said housing, abutment means on said firing pin slidably within said shoulder means, a collar slidably mounted on said firing pin and engageable with said shoulder means, a retractor spring on said firing pin compressible between said collar and said holder for resiliently retaining said firing pin out of said aperture, a stud projecting radially from said holder through

and slightly beyond said slot, and a sleeve rotatably mounted on the exterior of said housing including an internal annular groove receiving said stud and defining a plurality of cam surfaces engageable therewith, said mechanism being constructed and arranged whereby rotation of said sleeve in one direction is operative to position said stud in one of said branches compressing said firing spring and cocking said firing pin, and reverse rotation of said sleeve is operative to release said stud from said one branch, continued reverse rotation causing said stud to be seated in the other of said branches compressing said retractor spring and extending said firing pin through said aperture.

2. A gun firing mechanism comprising, a breech closure having an aperture therein, a generally tubular housing threadedly engaged with said closure including a longitudinal slot in the outer periphery thereof having oppositely extending circumferential branches adjacent to its opposite ends, a firing pin and holder secured together for joint reciprocation within said housing, a firing spring mounted for compression between said holder and an end wall of said housing, shoulder means in said housing, abutment means on said firing pin slideable within said shoulder means, a collar slidably mounted on said firing pin and engageable with said shoulder means, a retractor spring on said firing pin compressible between said collar and said holder for resiliently retaining said firing pin out of said aperture, a stud projecting radially from said holder through and slightly beyond said slot, and a sleeve rotatably mounted on the exterior of said housing including an internal annular groove receiving said stud and defining a plurality of cam surfaces engageable therewith, said mechanism being constructed and arranged whereby rotation of said sleeve in one direction is operative to position said stud in one of said branches compressing said firing spring and cocking said firing pin, and reverse rotation of said sleeve is operative to release said stud from said one branch, continued reverse rotation causing said stud to be seated in the other of said branches compressing said retractor spring and extending said firing pin through said aperture.

3. A gun firing mechanism comprising, a breech closure having an aperture therein, a housing engaged with said closure including a longitudinal slot in the outer periphery thereof having oppositely extending circumferential branches adjacent to its opposite ends, a firing pin reciprocable within said housing, a firing spring urging said firing pin toward said aperture, shoulder means in said housing, abutment means on said firing pin, a collar slidably mounted on said firing pin and engageable with said shoulder means, a retractor spring on said firing pin, a stud connected to said firing pin and projecting through and slightly beyond said slot, and a sleeve rotatably mounted on the exterior of said housing including an internal annular groove receiving said stud and defining a plurality of cam surfaces engageable therewith, said mechanism being constructed and arranged whereby rotation of said sleeve in one direction is operative to position said stud in one of said branches compressing said firing spring and cocking said firing pin, and reverse rotation of said sleeve is operative to release said stud from said one branch, continued reverse rotation causing said stud to be seated in the other of said branches

compressing said retractor spring and extending said firing pin through said aperture.

4. A gun firing mechanism comprising, a breech closure having an aperture therein, a housing engaged with said closure including a longitudinal slot in the outer periphery thereof having offset branches adjacent to its opposite ends, a firing pin reciprocable within said housing, a firing spring urging said firing pin toward said aperture, means for resiliently retaining said firing pin out of said aperture, a stud connected to said firing pin and projecting through and slightly beyond said slot, and a sleeve rotatably mounted on the exterior of said housing including an internal annular groove receiving said stud and defining a plurality of cam surfaces engageable therewith, said mechanism being constructed and arranged whereby rotation of said sleeve in one direction is operative to position said stud in one of said branches compressing said firing spring and cocking said firing pin, reverse rotation of said sleeve causing said stud to be seated in the other of said branches and extending said firing pin through said aperture.
5. A gun firing mechanism comprising, a breech closure having an aperture therein, a housing attached to said closure and including means forming a longitudinal through slot therein having offset branches extending therefrom, a firing pin in said housing, a firing spring urging said firing pin toward said aperture, a stud connected to said firing pin and projecting through and beyond said slot, and a sleeve enclosing said slot including means forming a plurality of cam surfaces engageable with said stud and constructed and arranged whereby successive opposite rotation of said sleeve alternately positions said stud in each of said branches.

6. A gun firing mechanism comprising, a housing, means forming a longitudinal through slot in said housing having an offset branch extending therefrom, a firing pin in said housing, a stud connected to said firing pin and projecting through and beyond said slot, and a sleeve enclosing said slot including means forming a cam surface engageable with said stud and constructed and arranged whereby rotation of said sleeve positions said stud in said branch.

7. A gun firing mechanism comprising, a breech closure having an aperture therein, a housing threadedly engaged with said closure, a firing pin reciprocable in said aperture, a holder secured to said firing pin for joint reciprocation within said housing, a firing spring mounted for compression between said holder and an end wall of said housing, abutment means on said firing pin slideable within said housing into contact with the said breech closure adjacent the said aperture to effect a gas tight seal to prevent flow of propellant gas to the said housing, and means for cocking and releasing the firing pin.

8. A gun firing mechanism comprising a breech closure having an aperture therein, a housing threadedly engaged with said closure, a firing pin reciprocable in said aperture, a holder secured to said firing pin for joint reciprocation within said housing, a firing spring mounted for compression between said holder and an end wall of said housing, abutment means on said firing pin to limit the forward movement of the firing pin and seal the said aperture against passage of propellant gases to the said housing, and means for cocking and releasing the firing pin.
